CLAIM

We claim the ornamental design for a countertop, as shown and described.

DESCRIPTION

FIG. 1 is a perspective view of a countertop showing our new design;

FIG. 2 is a top plan view thereof;

FIG. 3 is a bottom plan view thereof;

FIG. 4 is a front elevation thereof;

FIG. 5 is a rear elevation view thereof;

FIG. 6 is a right side elevation view thereof;

FIG. 7 is a left side elevation view thereof; and,

FIG. 8 is another perspective view thereof shown in an exemplary environment.

The broken lines illustrate portions of the article and environmental structure and form no part of the claimed design.

1 Claim, 5 Drawing Sheets
